UNITED STATES PATENT OFFICE.

JAMES MCKENNA, OF TORONTO, ONTARIO, CANADA, ASSIGNOR TO THE BEISTLE COMPANY, OF SHIPPENSBURG, PENNSYLVANIA.

WHIRLIGIG.

1,321,836.

Specification of Letters Patent. Patented Nov. 18, 1919.

Application filed November 21, 1918. Serial No. 263,608.

To all whom it may concern:

Be it known that I, JAMES MCKENNA, citizen of Canada, residing at Toronto, in the Province of Ontario and Dominion of Canada, have invented certain new and useful Improvements in Whirligigs, of which the following is a specification.

This invention relates to an improved toy and more particularly to a whirligig and 10 has as its primary object to provide a device of this character employing display slides which, when the device is rotated, will be projected by centrifugal force into position for display.

15 The invention has as a further object to provide an arrangement wherein the display slides will be connected by resilient members tending to retract the slides and wherein said slides will be provided with color bands 20 or stripes so that when the slides are projected against the resiliency of said members, the color bands thereon will form gradually expanding or contracting color rings around the body as the speed of rotation of 25 the device is accelerated or retarded.

And the invention has as a still further object to provide a device of the above described character which will be constructed of few and simple parts and wherein said 30 parts may be readily assembled so that the device may thus be easily produced.

Other and incidental objects will appear during the course of the detailed description of the invention. In the drawings, 35 wherein I have illustrated the preferred embodiment of the invention and wherein similar reference characters designate corresponding parts throughout the several views:

40 Figure 1 is a perspective view of my improved device, this view showing in dotted lines, the manner in which the display slides of the device are adapted to be projected from the body thereof when the body is rotated.

45 Fig. 2 is a fragmentary sectional view of the device,

Fig. 3 is a perspective view showing the sections of the body of the device separated 50 and also illustrating the display slides in detail, and

Fig. 4 is a detail elevation showing the outer face of the rear body disk of the device.

55 In carrying the invention into effect my

improved whirligig is formed with a circular body made up of companion circular sections or disks 10 and 11 respectively, the disk 10 providing the back plate of the body and the disk 11 the front plate. Upon its 60 outer face the disk 10 is preferably provided with a central circular red colored area 12 around which is a band of white 13 and encircling this white band at the margin of the disk is a band of blue 14. The inner 65 face of the disk is white. The disk 11 is, as shown in Fig. 3, of skeleton construction and comprises a ring 15 between opposite sides of which extend parallel chordal cross bars 16 intersected by a diametric cross bar 70 17 having a widened central portion 18 lying between the cross bars 16. These several cross bars thus define a plurality of substantially triangular shaped openings 19 at the outer sides of the cross bars 16 and oppositely disposed oblong openings 20 between said cross bars at opposite sides of the central portion 18 of the cross bar 17. Upon each end of the cross bar 17 is a white stripe 21. The center portion 18 of this bar bears 80 a somewhat wider stripe 22 in the center of which is arranged axially of the disk a circular area of blue 23. The remaining area of the outer face of this disk or section is colored red. The disks or sections 10 and 11 85 may be constructed of cardboard or other approved material, and, as particularly brought out in Fig. 2, are of equal diameter. Formed through the disk 10 adjacent its periphery are diametrically disposed openings 24. The disk 11 is provided with similar openings 25 adapted to register with the openings 24 and fitted through these registering openings are staples 26 having their free ends rebent against the outer face of 90 the disk 10 for thus connecting the disks to form the body of the device. The disk 10 at opposite sides of its axis is provided with spaced openings 27, and formed through the widened central portion 18 of 100 the cross bar 17 of the disk 11 is a similar pair of spaced openings 28 registering with the openings 27 and receiving the overlapping strands of the loop of a cord or other approved flexible element 29 therethrough. 105 This loop may, of course, be of any approved length. Slidably mounted between the disks or sections 10 and 11 of the body is a radially expandable center plate or disk made up of a pair of semi-circular sections 110

or display slides 30. Adjacent their inner edges these slides are, upon the front faces thereof, each provided with a substantially semi-circular area of red 31 about the curved 5 edge of which extends a stripe 32 of white and beyond this white stripe is a substantially crescent shaped stripe of blue 33. The rear faces of the slides are white. At their inner straight edges the slides are cut away 10 centrally to provide an opening 34 for freely receiving the strands of the loop 29 and formed in each of the slides from this opening is a reversely curved pair of radially extending incisions or slits 35 terminating in 15 openings 36. Inserted through the slits 35 to engage in corresponding openings of the openings 36 in the slides are rubber bands or other similar resilient loops 37 extending at opposite sides of the slides therebetween 20 for yieldably connecting the slides and normally holding the inner straight edges thereof abutting. In this connection it will be observed that the outer end portions of the slits 35 are curved laterally and inwardly 25 in the direction of the straight edges of the slides to enter the openings 36 so that the members 37 will engage the imperforate portions of the walls of said openings and the accidental displacement of said members 30 from the openings through the slits thereby prevented. Formed in the slides are oppositely disposed radial slots 38 which freely receive the staples 26 therethrough so that these staples thus act to slidably connect the 35 slides with the body of the device.

The manner in which the cord 29 is grasped and employed for rotating the device will be well understood. Normally, the members 37 will act to hold the slides 30 40 retracted upon the body of the device between the disks or sections 10 and 11 thereof. However, when the body is rotated, these slides will, by centrifugal action, be separated and projected against the tension 45 of said members radially with respect to the axis of rotation of the body. Furthermore, as the speed of rotation of the body is accelerated, the slides will be correspondingly advanced outwardly while as the speed 50 of rotation of the body is retarded, the slides will be retracted inwardly by the members 37. Consequently, it will be seen that when the device is viewed from the rear, the disk or section 10 will present three moving bands 55 colored red, white and blue, while the slides will, owing to the practical impossibility of rotating the body at a uniform speed, present a constantly expanding or contracting moving band of white around the band 60 of blue. In this connection it will, of course, be understood that the staples 26 will support and guide the slides 30 in their radial movement. When the device is viewed from its front side a band of blue will be seen at 65 the center of the device, this band of blue.

being formed by the blue area 23 upon the front disk or section 11. Around this band of blue the stripe 22 will form a band of white. Around this band of white, the red upon the bars 16 lying between the stripe 22 70 and the white stripes 21, will form a well defined band of red and since, as shown in Figure 1, the red areas 31 upon the slides 30 will show through the openings 19 and 20, said areas will form a less well defined 75 band of red gradually expanding or contracting for the reason previously stated. The white bands 32 upon the slides will also show through the openings 19 and 20 and as 80 also brought out in Fig. 1, the areas of red 80 31 upon the slides are intersected by the white stripes 21 upon the bar 17 while the white bands are intersected by the red cross bars 16. Consequently, when the device is rotated at a relatively low speed so that the 85 white band will not be moved out of view beneath the ring 15, a mottled band of red and white will be seen around the band of red formed by the red areas 31. Then, when 90 the speed of rotation of the device is accelerated the band of red formed by the areas 31 will disappear and a clear band of white will appear in lieu thereof, this clear 95 band of white being formed by the white inner face of the disk or section 10 and being defined and surrounded by a band of red 100 formed by the ring 15. When the speed of rotation of the device is thus accelerated the areas of red 31 will be projected at the periphery of the body of the device to form a band of red immediately surrounding the body. Around this band the stripes 32 will form a band of white, while around this band of white the areas 33 upon the slides will form a band of blue. It will thus be 105 seen that the colors of the device will change as the speed thereof is accelerated or retarded and by the arrangement of colors shown, I provide a highly attractive toy of the present character. The red, white and 110 blue bands seen at the periphery of the body of the device, when the device is rotated at a relatively high rate of speed will, for the reason herein given, also gradually 115 expand or contract so that these bands will have the appearance of gradually unfolding one out of the other, as the speed of the device is accelerated, or gradually fading one into the other as the speed of the device is retarded. This kaleidoscopic effect produced by the device will prove one very 120 fascinating to observe. However, I do not wish to be limited to any particular arrangement of colors as different combinations of the same colors or various combinations of 125 different colors may be resorted to without departing from the spirit of this invention.

Having thus described the invention, what is claimed as new is:

1. A device of the character described in- 130

- cluding a body formed of companion outer side plates, display members slidable between said plates, stationary means connecting the plates and extending freely 5 through said members for slidably connecting the members with the plates, and means for rotating the body whereby to shift the members outwardly thereon by centrifugal force.
- 10 2. A device of the character described including companion slides, companion outer side plates seating flat against the side faces of the slides and spaced apart thereby, spaced stationary connecting means extending 15 between the plates the slides being freely engaged with said means respectively whereby the slides may shift relative thereto, and means for rotating the plates.
3. In a device of the character described, 20 the combination of a solid rear side plate, a skeleton front side plate provided with color areas, spaced connecting means extending between the plates, companion slides disposed between the plates and each engaged 25 by a corresponding one of said connecting means whereby the slides may shift relative
- to said means and relative to the plates, the slides being provided with color areas visible through the skeleton front side plate, and means for rotating the plates whereby to 30 shift the slides outwardly therebetween and cause the color areas of the slides to disappear from view through the skeleton front side plate and appear beyond the outer edge of said plate blending with the color areas 35 upon the front plate.
4. A device of the character described including companion outer side plates, spaced connecting means extending between the plates, companion slides disposed between 40 the plates and each engaged by a corresponding one of said connecting means whereby the slides may shift radially with respect to the plates, the slides being formed with slots entering through the inner edges 45 of the slides and terminating in openings, yieldable means insertible through said slots and engaged in said openings for connecting the slides, and means for rotating said plates.

In testimony whereof I affix my signature.
JAMES McKENNA. [L.S.]
